LUGGAGE COVER HAVING SIDE AND END
WALLS LATERALLY STRETCHABLE AND
LONGITUDINALLY YIELDABLE

Irving Joseph Meyers, Richmond, Va.

Application October 12, 1948, Serial No. 54,069

7 Claims. (Cl. 190—26)

1

This invention relates to hand luggage, or the like and more specifically relates to protective covering devices for use with articles of this kind for maintaining exterior surfaces of such articles in good condition as well as providing a neat appearance.

One of the features of this invention is a protective covering for articles of luggage and the like, said covering being elastically expandible to conform with the contour of the article and being easily and quickly removed for cleaning.

Another feature of the invention is an elastically expandible protective covering for articles of luggage and the like, said covering being provided with a closure of the slide fastener type for quickly and easily removing the covering when desired.

A further feature of the invention relates to a construction by which the slideable fastener mounting is designed to be extensible and contractible so as to make it possible for the slideable fastener portion of the covering to adjust itself automatically to slight variations in the perimeter of the luggage around which the slideable fastener extends.

Other objects and advantages of the invention will appear obvious to one skilled in the art after studying the accompanying specification and drawings in which:

Fig. 1 presents an end view of a cover embodying this invention;

Fig. 2 is a plan view, from which a corner is cut away, and is taken at right angles to Fig. 1;

Fig. 3 is a front elevation;

Fig. 4 is a vertical cross-section taken along the line 4—4 of Fig. 2;

Fig. 5 is a cross-section also taken along the line 4—4 of Fig. 2 but showing a modified form of the cover;

Fig. 6 is a partial cross-section taken along the line 6—6 of Fig. 2;

Fig. 7 is a partial cross-section taken along the line 7—7 of Fig. 3;

Fig. 8 is an enlarged and detailed perspective view of a corner of the device with certain portions of the material stretched out of its normal position; and

Fig. 9 is a cross-section taken on the line 9—9 of Fig. 8.

Referring now to the drawings in detail, an article of luggage, such as a suitcase or the like, is indicated by the reference numeral 10, provided with a carrying handle 11. Such an article has top, bottom, back and side surfaces, of which the top and bottom surfaces usually lie in parallel

2

planes spaced from each other and are joined at right angles along their edges by the back and side surfaces. For convenience, it has been assumed that the back surface of the article 10 is usually flat and provided with hinge means, and that whereas in the preferred embodiment, as shown, the side surface comprises three flat side and end wall surfaces forming, with the back side, a rectangular enclosure joining the opposing edges of the top and bottom surfaces, the side surface might take a cylindrical form as in the case of a hat box, or similar article, of conventional design. The side surface is usually split along a line co-extensive with the line of the hinge means, to permit the article to be opened and closed.

The portion of the protective covering which covers the top of the article is indicated by the reference numeral 12, the portion covering the back surface is shown at 13, and the portion covering the bottom surface at 14. These portions of the covering are preferably made of a single piece of inelastic flexible material, such as canvas, or any similar fabric, or synthetic material which will have resistance to wear and be reasonably light in weight. The portions 12, 13, and 14 should be cut to approximately the same dimensions as the equivalent surfaces of the article but these measurements are not critical inasmuch as the side and end wall portion 15 is composed of a material which has uni-direction elasticity, such as any suitable one-way stretchable elastic cloth of conventional manufacture. The side and end wall portion 15 is joined to the opposing edges of the top surface 12, and the bottom surface 14, but it is not joined to the edges of the back surface 13. The portion 15 may be joined to the portions 12 and 13 by such means as sewing, and this seam may be covered by a decorative tape 16 which may also extend in a continuous length along the edges of the back portion 13. Furthermore, the portion 15 is attached to the top portion 12 and the bottom portion 14 in a manner to permit stretching of the side and end wall portion only in a direction normal to the line of the seam. This permits the covering to adjust itself to changes in shape of an article and to conform neatly and snugly to the contour of the enclosed article regardless of whether it may have its normal shape when empty, or whether it may be bulging and deformed as a result of being tightly packed. Closure means 17 of the slide fastener type have been provided in the side and end wall portion 15, and in the preferred embodiment two such devices,

provided with operating means 18, have been shown extending nearly the entire length of the side and end wall portions 15 to allow handle 11 to the direction of elasticity of the material. A suitable opening 19 has also been provided in the side and end wall portion 15 to allow handle 11 of the article 10 to pass through. Certain of the features above described and shown have been disclosed and claimed in my co-pending application Serial Number 3,780, filed January 22, 1948 with respect to which this invention is an improvement.

It has been found in the use of my prior protective covering that, if the side surface of the enclosed article, due to being too tightly packed, bulged too far outwardly, it was difficult to operate the slide fastener closure due to the fact that such a closure is incapable of being stretched in a longitudinal direction, and no provision was made to relieve strains normal to the direction of elasticity of the side covering portion. In the present device the side portion 15 has been provided with free unattached end portions 21 which extend from the points 20 and 20a in the seams joining portion 15 to portions 14 and 12 respectively, and is shown in detail in Figs. 8 and 9. An elastic means 22, overlying the back portion 13, extends over at least a portion of the back surface of article 10 and joins the free ends 21 in a seam 23. Preferably the means 22 is capable of uni-directional elasticity and is similar to the material used in the side and end wall portion 15. However, any suitable elastic material or device may be used, the only criterion being that it be stretchable in a direction at right angles to the direction of elasticity of the side and end wall portion 15, as the purpose of this part of the covering is to permit the side and end wall portion 15 to adjust itself to bulges in the side surface of the enclosed article and in so doing not to require the closure means 17 to be put under a longitudinal strain. For purposes of showing the details of construction, the seam 23 in Figs. 8 and 9 has been illustrated as pulled out from behind the back portion 13, but it will be understood that in normal use this seam will preferably assume a position as shown in Fig. 7. In effect this improved construction provides the equivalent of a slideable fastener which is extensible and elastically stretchable, lengthwise.

Fig. 5 shows a modified form of the device in which the resilient means 22 is not joined directly to the free end portions 21, but is sewed at its ends to pieces of ordinary fabric or suitable material 24 by means of seams 26, while other seams, similar to seams 23, join the material 24 to the free ends 21.

I claim:

1. An expandable protective covering for snugly enclosing an article of luggage or the like having top, bottom, back, and side surfaces, comprising substantially inelastic flexible material for covering the top, back, and bottom surfaces of the article, substantially uni-directionally elastic flexible material extending over the side surface of the article and joined to opposing edges of the material which covers the top and bottom surfaces, substantially uni-directionally elastic flexible material extending over at least a portion of the back surface of the article and joining free ends of the first-mentioned elastic material, the direction of expansion of said first-mentioned elastic material substantially being at right angles to the direction of expansion of said sec-

ond-mentioned elastic material, and slide fastener closure means provided in said covering to permit removal of the article.

2. An expandable protective covering for snugly enclosing an article of luggage or the like having top, bottom, back, and side surfaces, comprising substantially inelastic flexible material for covering the top, back, and bottom surfaces of the article, substantially uni-directionally elastic flexible material extending over the side surface of the article and joined to opposing edges of the material which covers the top and bottom surfaces, free ends of said elastic material extending over a portion of the back surface of the article and overlying the inelastic material, substantially uni-directionally elastic flexible material extending over at least a portion of the back surface of the article and joining said free ends of the first-mentioned elastic material, the direction of expansion of said first-mentioned elastic material being substantially at right angles to the direction of expansion of said second mentioned elastic material, and slide-fastener closure means provided in the elastic material covering the side surface of the article.

3. An expandable protective covering for snugly enclosing an article of luggage or the like having top, bottom, back, and side surfaces, comprising substantially inelastic flexible material for covering the top, back, and bottom surfaces of the article, substantially uni-directionally elastic flexible material extending over the side surface of the article and joined to opposing edges of the material which covers the top and bottom surfaces, said elastic material being provided with unattached free end portions, said elastic material being provided with closure means of the slide fastener type extending in a direction normal to the direction of elasticity of said material, the free end portions of said uni-directionally elastic material extending over a portion of the back surface of the article and overlying the inelastic material, elastic flexible material extending over a portion of the back surface of the article and joining the free end portions of the uni-directionally elastic material.

4. An expandable protective covering for snugly enclosing an article of luggage or the like having top, bottom, back, and side surfaces, comprising substantially inelastic flexible material for covering the top, back, and bottom surfaces of the article, substantially uni-directionally elastic flexible material extending over the side surface of the article and joined to opposing edges of the material which covers the top and bottom surfaces, said elastic material being provided with unattached free end portions, said elastic material being provided with closure means of the slide-fastener type extending in a direction normal to the direction of elasticity of said material, the free end portions of said uni-directionally elastic material extending over a portion of the back surface of the article and overlying the inelastic material, elastic flexible material extending over at least a portion of the back surface of the article, and means for joining the free end portions of the uni-directionally elastic material to opposite ends of said elastic material extending over the back surface of the article, said means including a length of inelastic flexible material.

5. An expandable protective covering for snugly enclosing an article of luggage or the like having top, bottom, back, and side surfaces, comprising substantially inelastic flexible

material for covering the top, back and bottom surfaces of the article, substantially uni-directionally elastic flexible material extending over the side surface of the article and joined to opposing edges of the material which covers the top and bottom surfaces, said uni-directionally elastic material being provided with closure means of the slide-fastener type extending in a direction normal to the direction of elasticity of said material, elastic, flexible material overlying said inelastic material and extending over a portion of the back surface of the article and joining free end portions of the uni-directionally elastic material.

6. An expandible protective covering for snugly enclosing an article of luggage or the like having top, bottom, back, and side surfaces, comprising substantially inelastic flexible material for covering the top, back, and bottom surfaces of the article, substantially uni-directionally elastic flexible material extending over the side surface of the article and joined to opposing edges of the material which covers the top and bottom surfaces, said uni-directionally elastic material being provided with unattached free end portions, said uni-directionally elastic material being provided with closure means of the slide-fastener type extending in a direction normal to the direction of elasticity of said material, elastic flexible material overlying said inelastic material and extending over a portion of the back surface of the article, and means for joining the free end portions of the uni-directionally elastic material to opposite ends of said elastic material extending over the back surface of the article, said means including a length of inelastic flexible material.

7. An expandible protective cover for snugly enclosing an article of luggage or the like, having top, bottom, back and side surfaces, comprising flexible material for covering the top, back and bottom surfaces of the article, elastic flexible material extending over the side surfaces of the article, and stretchable in a direction between top and bottom and joined to opposing adjacent edges of the material which covers the top and bottom surfaces, said elastic material being provided with end portions not attached to each other and located adjacent the bottom surface of the article, said elastic material being provided with closure means of the slideable fastener type extending along the side surfaces of the article and parallel to the adjacent edges of the top and bottom, elastic flexible material overlying said first mentioned flexible material and extending over a portion of the back surface of the article, and having its opposite ends connected to that material on which said slideable fastener is mounted, whereby the position of said slideable fastener with respect to the sides and back of the article is yieldably adjustable.
